United States Patent Office

Des. 180,449
Patented June 11, 1957

180,449

AUTOMOBILE FLOOR MAT

Emanuel Meyer, Latham Park, Pa.

Application April 18, 1956, Serial No. 41,119

Term of patent 14 years

(Cl. D9—6)

FIG. 1.

FIG. 2.

FIG. 3.

Fig. 1 is a top plan view of an automobile floor mat embodying my new design;

Fig. 2 is a sectional view taken along lines II—II of Fig. 1, a portion being shown broken away for the convenience of illustration; and

Fig. 3 is a sectional view taken along line III—III of Fig. 1.

I claim:

The ornamental design for an automobile floor mat, as shown.
